poration of Kansas

Application April 5, 1954, Serial No. 29,854

Term of patent 14 years

(Cl. D14—3)

To all whom it may concern:

Be it known that I, William J. Haynes, Sr., a citizen of the United States, residing at Bonner Springs, in the county of Wyandotte and State of Kansas, have invented a new, original, and ornamental Design for a Cart for Fireplace Wood, of which the following is a specification, reference being had to the accompanying drawing, forming a part thereof.

Fig. 1 is a front elevational view of the cart for fireplace wood, showing my new design;

Fig. 2 is a rear elevational view thereof;

Fig. 3 is a side elevational view thereof; and

Fig. 4 is a top plan view thereof.

The dominant features of my design reside in the por-
tions shown in full lines.

I claim:

The ornamental design for a cart for fireplace wood, as
shown and described.
